Primary Examiner — John Windmuller(74) *Attorney, Agent, or Firm* — Duane Morris LLP; J. Rodman Steele, Jr.; Gregory M. Lefkowitz**CLAIM**

The ornamental design for a toilet aid device, as shown and described.

DESCRIPTION

FIG. 1 is a perspective view of a toilet aid device;

FIG. 2 is a front view thereof;

FIG. 3 is a top view thereof;

FIG. 4 is a bottom view thereof;

FIG. 5 is a left side view thereof; and,

FIG. 6 is a right side view thereof.

The back view is a mirror image of the front view shown in FIG. 2.
